ELECTRON GUN STRUCTURE

Walter R. Beam, Hamilton Square, and Ronald C. Knechtli, Cranbury, N.J., assignors to Radio Corporation of America, a corporation of Delaware

Application August 17, 1956, Serial No. 604,645

4 Claims. (Cl. 315—16)

This invention relates to electron guns for cathode ray tubes or kinescopes, and it has for its object to provide a novel high voltage limiting aperture electron gun of improved performance.

Another object of the invention is to decrease the spot size in an electron gun of the above type for a given current and gun length.

A further object is to provide an electron gun of the above type in which less voltage is required at the limiting aperture for a given peak current, and in which less power is dissipated by this aperture.

Still another object is to provide a high voltage limiting aperture electron gun having improved cut-off and beam modulation characteristics.

Various other objects and advantages will be apparent as the nature of the invention is more fully disclosed.

In any situation where a very small spot on the phosphor screen of a cathode ray tube or kinescope is required, the normal type of electron gun is not suitable. The spot obtained therefrom is of variable size, depending on the beam current. Furthermore, the spot edges are not sharply defined. In a high voltage limiting aperture gun, the spot is practically of constant size because the object is not a "crossover" of electron paths, but a mechanically defined aperture. With the limiting aperture operated at high voltage (500 v. or more) the effects of space charge and of chromatic aberrations become negligible, and the sharpness of definition of the spot is determined by the aberration of lenses alone.

The present invention provides a high voltage limiting aperture gun of improved performance which includes a cathode and electrode means for producing a convergent electron beam, a modulating electrode having an aperture which is disposed in the path of the convergent beam, and an object-forming electrode disposed along the path of travel of the beam beyond said modulating electrode. The said object-forming electrode has a limiting aperture formed therein for the passage of the beam, the size of which aperture is smaller than the transverse size of the beam for sharply defining the transverse size and configuration of the beam upon its emergence from said limiting aperture. The novel construction, hereinafter described in detail, results in a significant reduction in the magnification of the spot with respect to the limiting aperture, and accordingly permits the production of a smaller size spot with more sharply defined edges than in the case of previous electron guns of this general type.

The invention is described more in detail in connection with the accompanying single sheet drawing in which Fig. 1 is a sectional view of a cathode ray tube employing an electron gun in accordance with this invention, Fig. 2 is an enlarged sectional view of the electron gun of Fig. 1.

The electron gun shown in the drawing is mounted within a tube envelope 26 and comprises a cathode K with a concave electron emitting surface 1 at one end.

Disposed beyond the cathode K is an annular electrode G₁ mounted by supports 2 coaxially with the cathode. A second electrode G₂ is positioned by supports 3 beyond the annular electrode G₁ and has a central aperture 4 formed therein through which the electron beam passes. The structure thus far described comprising the cathode K and the electrodes G₁ and G₂ is of the type generally known as a "Pierce" gun (see Spangenberg's "Vacuum Tubes," pp. 449-465).

10 The "Pierce" gun K—G₁—G₂ produces a convergence electron beam which passes through straightening and object-forming electrodes G₃ and G₄, respectively. The straightening electrode which is designated generally as G₃, is mounted by supports 5 and is provided with a central aperture 6 through which the beam passes, the aperture 6 being coaxially aligned with the elements K—G₁—G₂ of the "Pierce" gun. The aperture 6 is formed in a thin flat disc 7 which is secured to a dished annular member 9 so that the aperture 6 is offset toward 20 the cathode.

The object-forming electrode G₄, which is mounted by supports 10, is disposed along the direction of travel of the beam beyond the straightening electrode G₃. Electrode G₄ is of shouldered cylindrical configuration 25 and comprises a flanged cylindrical body portion 11 having an open end upon which a thin centrally apertured guide disc 12 is mounted. Secured to the guide disc 12 on the side toward the cathode K is a thicker disc 13, preferably formed of molybdenum. The disc 30 13 has a central limiting aperture 14 formed therein coaxially aligned with cathode K and the apertures in electrodes G₁, G₂ and G₃. In certain embodiments of the invention the limiting aperture 14 may be rectangular, say 0.015 inch long by 0.004 inch wide, where 35 a spot of rectangular shape is desired on the screen of the tube in which the gun is used.

Terminals 16, 17, 18, 19 and 20 are provided for the individual application of suitable potentials to the cathode K and electrodes G₁, G₂, G₃ and G₄, respectively.

40 The operation of the electron gun is as follows: To obtain a spot of given size, from electrons emerging from a limiting aperture of given size, such as aperture 14, the magnification M of the gun is fixed. The amount of magnification M is, of course, desirably made 45 as small as possible, to keep the spot on the screen as small as possible. The magnification M is given by the following expression:

$$50 M = \sqrt{\frac{V_{\text{aperture}}}{V_{\text{screen}}}} \frac{\sin(\theta_{\text{aperture}})}{\sin(\theta_{\text{screen}})} = \frac{\text{Dimension of spot}}{\text{Dimension of aperture}}$$

The two V's are potentials at aperture and screen, θ_{aperture} and θ_{screen} are the angles that a given ray (for example, the outermost ray) makes with the axis at aperture and screen, respectively. Guns and yoke distortions and tube size fix the value of θ_{screen} for the outermost rays. In order to make M as small as possible, V_{aperture} and θ_{aperture} must be as small as possible.

60 In any electron gun for a cathode ray tube, the thermal limitation to current density in the spot is given by:

$$65 J_{\text{max screen}} = J_{\text{cath}} \left(\frac{11,600 V_{\text{screen}}}{T_{\text{cathode}}} \right) \sin^2 \theta_{\text{screen}}$$

where J_{cath} is the current density at the cathode. In a limiting-aperture gun, there is also a thermal limitation at the aperture:

$$70 J_{\text{max aperture}} = J_{\text{cath}} \left(\frac{11,600 V_{\text{aperture}}}{T_{\text{cath}}} \right) \sin^2 \theta_{\text{aperture}}$$

Taking the ratio of these maximum current densities, we obtain:

$$\frac{J_{\max \text{ screen}}}{J_{\max \text{ aperture}}} = \frac{V_{\text{screen}} \sin^2 \theta_{\text{screen}}}{V_{\text{aperture}} \sin^2 \theta_{\text{aperture}}} = \frac{1}{M^2}$$

This indicates that if the limitation is reached at the aperture, the same will be true at the screen, hence the problem of designing such a gun is resolved into obtaining the most current at the least value of $V_{\text{ap}} \sin^2 \theta_{\text{ap}}$.

Applying these considerations, in one embodiment of the invention, we operate the straightening electrode G_3 with a biasing potential of 150 volts and with a potential of 1500 volts applied to object-forming electrode G_4 , the inter-aperture spacings 4—6 and 6—14 each being about $\frac{1}{16}$ inch. This produces a value of 2.1 for $\sqrt{V_{\text{aperture}} \sin \theta_{\text{aperture}}}$ with a beam current of 1 milliampere as contrasted with other known forms of gun construction which may give a value of 6 or more for this important performance factor.

The electron beam from cathode K is convergent until it has passed through the aperture 4 in G_2 . Then the amount of convergence is decreased by the action of the strong aperture lens caused by G_2 and the decelerating field in the region from G_2 to G_3 . After passing through the aperture 6 in G_3 , the beam is accelerated in a uniform field which has a "straightening out" effect, the reduction in convergence angle being about $\frac{1}{2}$ by the time the beam reaches the limiting aperture 14.

The beam passing through the limiting aperture 14 is then focused on screen 21 by focusing electrodes 22, 23 and wall coating 24 which are maintained at appropriate voltages during tube operation. The beam is deflected over screen 21 by magnetic deflecting fields provided by coils mounted in yoke 25.

What is claimed is:

1. An electron gun structure comprising a cathode means having a concave electron emitting surface, an annular electrode adjacent to said cathode surface and having a frusto-conical surface facing away from said cathode for focusing electrons emitted from said cathode

surface into a convergent electron beam, a convergence reducing straightening electrode having an aperture formed therein which is disposed in the path of said beam for passage of said beam therethrough, and an object-forming electrode disposed along the path of travel of said beam beyond said straightening electrode, said object-forming electrode having a limiting aperture formed therein for passage of said beam therethrough, the size of said limiting aperture being smaller than the transverse size of said beam for sharply defining the transverse size and configuration of said beam upon its emergence from said limiting aperture.

2. The combination according to claim 1, in which said aperture in said straightening electrode is larger than said limiting aperture.

3. The combination according to claim 2, further comprising means for maintaining said object-forming electrode at a high potential with respect to said cathode means, and means for maintaining said straightening electrode at a potential considerably less than the potential on said object-forming electrode, whereby said beam is accelerated during its passage from said straightening electrode to said object-forming electrode and thereby made more parallel to the axis of the gun.

4. The combination according to claim 3, in which the magnitude of said potential on said object-forming electrode is at least five times as great as said potential on said modulating electrode.
